BURGLARPROOF DOOR

Filed Dec. 7, 1927

UNITED STATES PATENT OFFICE

SAMUEL M. WEINSTEIN, OF CHICAGO, ILLINOIS

BURGLARPROOF DOOR

Application filed December 7, 1927. Serial No. 238,361.

This invention relates to burglar proof doors adapted for use in connection with apartments and dwellings or the like, and the object thereof is to construct a burglar proof door, the upper part of which is provided with a sight opening through which the occupant of the apartment or dwelling can view the party on the outer side of the door before opening the same when the door 5 bell rings, said upper part or panel having one or more transparent panels of bullet and burglar proof glass to provide the sight opening, and having an opaque movable or 10 slideable panel of wood or metal or other suitable material by means of which view from the outside can be excluded or the panel may be operated to admit light, sun or to permit view from the inside or outside when desired, though ordinarily the primary purpose 15 is to permit the occupant of the apartment or dwelling to operate the panel to view the party on the outside of the door before opening the door, thus providing a boon to the prevention of burglaries or robberies and 20 holdups which have been so common.

An important feature of the invention is the fact that there are inner and outer bullet-proof panels and a space between the same adapted to accommodate the movable panel, 25 and should a bullet pierce, crack or break the outer glass panel the inner one will prevent the bullet passing through and injuring the occupant.

Other objects and advantages will be apparent as the description proceeds.

In the accompanying drawings:

Figure 1 is a front elevation of a burglar proof door constructed in accordance with the invention.

Figure 2 is a sectional view taken vertically on the section line 2—2 of Figure 1, and

Figure 3 is a sectional view taken horizontally on the section line 3—3 of Figure 1.

Referring to the drawings in detail, in which like reference characters designate corresponding parts throughout the several views, 4 designates the frame of the door consisting of side sections or upright stiles 50 5 extending through the thickness thereof

and top and bottom sections or rails 6 and 7 respectively, the latter rail being preferably wider than the former but not necessarily so. The side sections 5 are grooved or mortised on the inside to provide central 55 grooves 8 between inwardly projecting ribs or tongues 9. The latter are spaced from the opposite faces of the door frame to provide rabbets or recesses 10 on opposite sides. The top and bottom sections 6 and 7 are similarly formed at their inner or bottom and upper faces respectively, and at their ends to fit the inner edges of the side sections and be glued thereto or otherwise fastened to 60 form the frame structure.

Within the grooves or slideway provided by the grooves 8 is fitted a slideable panel 11 of opaque material such as wood, metal or composition material if desired, but preferably wood since the same is light, although 65 metal may be used in view of its strength and additional protection provided. This panel is adapted to move in a pocket formed between the two sides of the door, preferably to slide up and down vertically and may 70 be operated in the same manner as automobile windows or in any other well known manner.

As shown, it is provided with a handle 12 having a shank 13 connected to the panel as 75 indicated at 14 near the lower edge of the latter and adapted to slide in a vertical slot 15 provided in a central strip 21 and intermediate portion of an inner panel 16 at the inner side and lower portion of the door 80 and corresponding to a similar panel 16 at the outer side of the door. These lower panels 16 are fitted in the recesses 10 and secured thereto in any well known manner. These panels are arranged below the 85 cross strips 17 extending between and connecting the side sections 5 and seated in the opposite recesses 10.

In the recesses 10 at opposite sides of the panel 11 which is slideable as heretofore described, are disposed burglar or bullet proof glass or other transparent, semi-transparent or translucent panels 18 which are secured in position in any well known manner as by 90 means of molding strips 19 at the sides and 95 100

at the top and bottom and on opposite sides of the door frame. This burglar proof and bullet proof glass is of the type now manufactured for armoured cars or the like and may be wired or not, as desired. It will be apparent from Figure 2 of the drawings that the transparent burglar proof and bullet-proof glass panels rest upon the cross strips 17 between which latter the movable or slideable panel 11 may pass due to the spacing of said strips 17 and it is obvious that the panels 18 may be of any suitable transparent material other than glass as long as the same is burglar proof and bullet proof.

The strips 17 preferably have ribs or tongues 20 which extend up between the movable panel 11 and the transparent means or panels as clearly shown in Figure 2. The vertical strips 21 are provided on the panels 16 spaced from the side sections 5 and connecting the bottom section 7 and strips 17. The panels 16, however, are each formed in one section as heretofore described and secured in position, reinforced and ornamented by the central vertical strips 21 and molding strips 22 on the opposite sides, while the strips 23 at the top and bottom are independent strips formed with or attached to the bottom section 7 and strips 17 at opposite sides of the strips 16. All of the molding strips are cut diagonally at the corners to fit together so that the strips 23 at the top and bottom give the effect of two strips to receive the reinforcing intermediate strips 21 of the panels 16 and the molding strips 22 where they meet with the bottom section 7 and the strips 17. The shank 13 is turned into a notch 15' to hold the panel 11 raised.

The panel 11 preferably terminates near the bottom of the opposite strips 17 as indicated in dotted lines in Figure 1 and as shown in Figure 2 while the panels 16 provide a space between them at the bottom to accommodate the panel 11 when lowered by movement of the handle 12 and its shank 13 in the slot 15 when turned and disengaged from a supporting position in the notch 15' and lowered by the occupant from the inside. When lowered, the movable panel 11 may be supported on a filler strip 24 disposed between the panel sections 16 as indicated at Figure 1 in dotted lines at the bottom of the door and clearly designated in section in Figure 2, so as to support the movable panel 11 when slid to the bottom position to provide a sight opening through which the occupant of the apartment or dwelling can view the party on the outer side of the door before opening the same. However, it is obvious that the movable or slideable panel 11 may be opened any desired distance and that the opening need only be sufficient to permit the view of the caller.

From the foregoing, it will be obvious that I have provided a very simple and desirable form of burglar proof door through which

the occupant may readily view a person calling at the door without opening the same and if an intruder, to prevent burglary or holdups hence the burglar proof and bullet-proof panels 18 will prevent bodily harm, as the same will prevent bullets piercing the door. However, the movable or slideable panel 11 instead of being of wood may be of metal to further facilitate this. Furthermore, it is to be understood that only one of the bullet-proof panels 18 may be provided on the outer side of the movable or slideable panel 11 and still accomplish the objects of the invention.

While I have described my invention in a preferred form, it is to be understood that various changes in the relations of parts and modifications may be made without departing from the spirit and scope of the invention.

What I claim is:

1. A burglar proof door having inner and outer bullet proof transparent panels near the top, a movable opaque panel between the same, the lower portion of the door being slotted, a handle carried by the opaque movable panel and extending into the slot for raising and lowering said movable panel and means to support the handle in a top position when the movable panel is disposed in a raised position over the bullet proof panels.

2. A burglar proof door having an opening through the upper part and formed in its lower part with a panel-receiving pocket intermediate the two sides of said door and communicating with said opening, an opaque panel slidably mounted with respect to said opening and pocket and adapted in its uppermost position to completely close said opening, and in its lower-most position to be housed in said pocket, operating means for said opaque panel, and panels of bullet proof transparent material closing the opposite sides of said opening.

In testimony whereof I affix my signature.

SAMUEL M. WEINSTEIN.
